INVENTOR
William F. Lorcy
By W. W. Williamson, Attn.

UNITED STATES PATENT OFFICE.

WILLIAM F. LOREY, OF PHILADELPHIA, PENNSYLVANIA.

ADJUSTABLE LAMP SUPPORT.

Application filed July 2, 1924. Serial No. 723,636.

My invention relates to new and useful improvements in an adjustable lamp support, and has for its primary object to provide an exceedingly simple and effective device of this character which may be adjusted horizontally, vertically and lengthwise in order to position a lamp supported on the outer end of an arm in any desirable location.

10 Another object of the invention is to provide an adjustable arm of two sections, one of which is slideable relative to the other and having a cooperating means of unique construction for holding the sliding section in 15 any adjusted position.

A further object of the invention is to provide a concavo-convex washer so constructed as to provide an annular knife edge which will bite into the member with which 20 it cooperates to reduce to a minimum the likelihood of movement thereby overcoming the possibility of the fastening bolt and nut becoming loose.

The device above mentioned constructed 25 in accordance with my invention is particularly useful about a work bench or other similar places as the lamp may be readily positioned to throw the light rays directly upon the work.

30 With these ends in view, this invention consists in the details of construction and combination of elements hereinafter set forth and then specifically designated by the claim.

35 In order that those skilled in the art to which this invention appertains, may understand how to make and use the same, I will describe its construction in detail, referring by numerals to the accompanying 40 drawing forming a part of this application, in which:—

Fig. 1, is a plan view of an adjustable lamp support embodying my invention.

Fig. 2, is a side elevation thereof.

45 Fig. 3, is an enlarged sectional plan view of the clip and swivel socket members.

In carrying out my invention as here embodied, 2 represents a suitable bracket for permanent attachment to a support such as 50 the wall of a building and said bracket includes a post 3 on which the swivel socket member 4 is journaled for a swinging adjustment in a horizontal plane and said swivel socket member is preferably formed 55 from a sheet of metal bent to produce a

socket 5 and parallel contacting plates 6 projecting from the socket.

The reference numeral 7 designates the clip member which is composed of two similar separate clips 8 the only difference being 60 that one is a right hand and the other a left hand clip and therefore but one of these will be described in detail. A clip 8 is made from a suitable strip of sheet metal so cut and fashioned as to provide a side wall 9, 65 a bottom wall 10, a fragmental top wall 11 and an end wall 12. From the upper edge of the side wall 9 projects an upright 13 having a hole 14 therein while from the end wall 12 projects a clamping plate 15. 70

Two of these clips are secured upon one end of an arm section 16, one on either side, and held in place by suitable fastening means such as a bolt 17 and nut 18, said bolt passing through both clips and the arm section 16. When thus in place the clamping plates 15 of both clips engage opposite sides of the swivel socket member 4. 75

Engaging each clamping plate 15 is a concavo-convex washer 19 with a bolt 20 passing through both of these, both clamping plates 15 and the plates 6 of the swivel socket member with a nut 21 threaded on said bolt. Each of these washers is so formed as to provide a beveled rim thus producing a 80 knife edge 22 which is the only part that will contact with a bearing plate and will therefore bite into said plate as pressure is applied and prevent rotation of a washer relative to the clamping plate on which it 85 bears and therefore the clip member may be swung vertically to different adjusted positions without the possibility of the fastening means becoming loosened. This is of considerable advantage in devices of this 90 character as the support will remain in the 95 position to which it is adjusted.

The arm section 16 of the longitudinally adjustable supporting arm has an L-shaped stop 23 secured to its upper edge at the 100 outer end, thus providing a tongue for registration with any one of a number of notches 24 in the lower edge of the sliding arm section 25, the latter being mounted to slide along the upper edge of the stationary 105 arm section 16. In order to hold the two arm sections in proper relation to each other, I provide two guide members 26 and 27 the former being fastened to the inner end of the arm section 25 and embracing the arm 110

16 while the guide member 27 is fastened to the outer end of the arm section 16 and embraces the arm section 25 but said guide member 27 is of sufficient size to permit the arm 25 to be raised high enough to disengage it from the stop 23 so that said arm section 25 may then be moved longitudinally relative to the stationary arm section 16 for adjusting the length of the supporting arm.

10 To the outer end of the sliding arm section 25 is secured a hook 28 on which is removably placed a hanger 29, said hanger being of sister-hook formation and in the hooked ends of said hanger are set the trunnions 30 of the lead-ball 31. The electric light cord 32 is placed between the uprights 13 where it is held against accidental displacement by a cross piece 33 in the form of a nail or the like inserted in the holes 14 in said uprights. This cord is then passed through the lead-ball 31 and has connected thereto in the usual or any approved way an electric lamp 34.

From the foregoing description it will be obvious that the adjustable or extensible arm may be adjusted horizontally about the post 3, vertically about the bolt 20 and lengthwise through the sliding arm section 25 thereby permitting the lamp to be located at any desired or preferred position.

Of course I do not wish to be limited to the exact details of construction as herein shown as these may be varied within the limits of the appended claim without departing from the spirit of my invention. 35

Having thus fully described my invention, what I claim as new and useful is:—

In a lamp support, a bracket, a socket member pivoted thereto for movement in a horizontal plane, a clip member pivoted to 40 the socket member for movement in a vertical plane and having opposed uprights connected together, a stationary arm section carried by the clip member beneath the connection of the uprights, a movable arm section 45 arranged for longitudinal sliding movement on the stationary arm section, said movable arm section having notches in its lower edge, a stop mounted on the upper edge of the stationary arm section at its outer end and having a tongue for registration with the notches in the other arm section, and means associated with the movable arm section to engage the free end of a lamp cord extending between the uprights and supporting a 50 lamp depending therefrom.

In testimony whereof, I have hereunto affixed my signature.

WILLIAM F. LOREY.
